METALLIC AWNINGS HAVING ADJUSTABLE LOUVERS AND LEVER-ACTUATING MECHANISM THEREFOR

Joseph De Martin, Brooklyn, N. Y.

Application June 1, 1950, Serial No. 165,499

2 Claims. (Cl. 20—57.5)

This invention relates to improvements in metallic awnings having adjustable louvers and lever-actuating mechanism therefor operable from within a room, and particularly to that type of metallic awning which is provided with a series of louvers or vanes which are pivotally mounted in a suitable fixed frame and are adjustable from inside a room to regulate the admission of sunshine, light or air and the exclusion of rain or wind.

In conventional awnings, it is common to provide a fixed metallic frame with a plurality of metallic louvers adjustably arranged therein, but most prior art structures as well as the actuating mechanism therefor have been quite complicated, cumbersome and heavy and such devices have not only been expensive to manufacture and to erect, but operation thereof has been either by flexible connections or rods located outside the window or like structure or when located within a room has been done by complicated winding mechanism and gearing positioned within and outside the house.

One of the objects of this invention is to simplify the structural characteristics of a metallic awning and its operating mechanism and to provide a device that may be manufactured at a greatly decreased cost; that may be readily and easily erected, and in which the louvers may be easily adjusted from full open to completely closed positions by a minimum movement of operating mechanism located within a room or the like; and with this end in view I provide an awning having adjustable louvers mounted to move to open and closed positions, respectively, by levers having pivot-fulcrums positioned closely adjacent to one end thereof to produce a long weight arm and a short power arm and preferably to utilize the louver itself as the opening and closing lever. I am thus enabled when such pivoted louvers are combined with proper operating mechanism not only to permit facile adjustment but to do so by a simple reciprocating movement of operating mechanism of minimum extent.

Another object of this invention is to enable operation of the louvers through a wall, window casing or the like by a straight horizontal rod having a short reciprocating movement and without the necessity of rotating or turning transmission rods with gearing or other outside devices.

Another object of my invention is in a device of the character specified that is operable through a wall, window frame or the like to utilize an outside mechanism including an upright reciprocating transmission rod having at its upper end a connection with a series of louver opening and closing levers, and at its lower operating end having a connection with a bell-crank lever which in turn is connected with a manually-actuated reciprocating rod.

With these and other objects in view, the invention comprises the combination of members and arrangement of parts so combined as to co-act and cooperate with each other in the performance of the functions and the accomplishment of the results herein contemplated, and com-

2

prises in one of its adaptations the species or preferred form illustrated in the accompanying drawings, in which:

Fig. 1 is a sectional view on the line 1—1 of Fig. 2 looking in the direction of the arrows of a metallic awning with transverse louvers mounted on a window frame;

Fig. 2 is a view in front elevation of the awning shown in Fig. 1;

Fig. 3 is a section on the line 3—3 of Fig. 1 looking in the direction of the arrows;

Fig. 4 is an enlarged section of my manually-reciprocable inside operating handle and rod connected with an outside bell-crank lever for transmitting movement to the louver-operating members;

Fig. 5 is a section on the line 5—5 of Fig. 6 showing a modified form with longitudinally-disposed louvers;

Fig. 6 is a plan view of the awning and mechanism illustrated in Fig. 5; and

Fig. 7 is an enlarged view of the fragmentary portion shown between the lines 7—7 of Fig. 6 broken away with parts in section taken on the line 7—7 of Fig. 5.

Referring now to these drawings and particularly to Figs. 1 to 3 thereof which illustrate a preferred embodiment of my invention, I have shown an awning preferably comprising a louver-embodying body portion 10 and side members 11. This awning is adapted to be fitted and fastened to the window frame 12 in any suitable manner, and my improvement consists in the construction and operation of the louvers in said body portion.

In accordance with the form of my invention shown in Figs. 1 to 3, the said body portion comprises a fixed metallic frame member 13 in which a series of louvers 14 are pivotally mounted and arranged to be adjusted from the full open position shown in dot and dash lines to the completely closed position shown in full lines in Fig. 1. The louvers are disposed transversely of the frame, and, as illustrated, each of the louvers 14 is provided on its under surface with a pivot-bearing bracket 15 in which is mounted a pivot fulcrum 16 projecting from the frame 13. Said bracket and pivot-fulcrum are positioned closely adjacent to one end and preferably to the upper end of each louver to produce in the louver a relatively long weight arm 16^a and a relatively short power arm 16^b. As illustrated, the end of each power arm has fixedly connected thereto one end of a short cleat 17, the opposite end 17^a of which is pivotally connected to a continuous louver-connecting member 18.

In the embodiment shown in Figs. 1 to 3 the louver itself is utilized as the opening and closing lever which swings about the pivot-fulcrum 16 to open and closed positions and I am thus enabled when such louvers are combined with proper operating mechanism not only to permit facile movement and adjustment of such louvers

but to do so by a simple reciprocating movement of minimum extent of such operating mechanism. In the embodiment shown in Figs. 1 to 3 the connecting member 18 is operated to open and close the louvers, as aforesaid, by means of an arcuately-movable transmission link lever 19 fixedly pivoted at one end 19^a to a bracket 20 fastened to the window frame 12 and connected at its

outer end 19^b by means of a slot-and-pin connection 19^c with the upper end of the louver-connecting member 18, and said fixedly-pivoted transmission-link 19 is engaged intermediate its ends at 19^d by an upright transmission rod 21 which extends downwardly to the lower portion

of the window frame and is connected at said lower end with operating-lever means comprising, as shown, a bell-crank lever 22 pivoted intermediate its ends at 22^e and having connected thereto at its lower end a straight rod 23 extending through the window frame into a room and provided within the room with a stationary mounting element and handle 24^a adapted for manual engagement

to reciprocate the rod 23 and thus to move the bell crank.

22. The handle 24 is preferably composed of a stationary part 24^a and a movable part 24^b which is fastened at 24^b to the rod 23, and in the preferred embodiment of my invention shown the stationary part 24^a of the handle member 24 is provided with a set screw 25 adapted to engage the rod and to hold the same at any particular position of movement thereof.

As illustrated, the bell crank lever is pivotally mounted upon a bracket 26 suitably fixed to the outside of the window frame and comprises a weight arm 22^b and a 10 power arm 22^c with which the rod 23 has a slot and pin connection at 23^a.

It will be seen from the above that I have combined with my adjustable louvers that are movable from full open to completely closed position by the movement of a short lever which consequently has a minimum of movement, lever means operable by a short reciprocating movement to operate said louvers to open and closed positions and to hold the same in any intermediate position. In the embodiment illustrated, the handle for operating my louver-adjusting mechanism is adapted to extend within the room only a very slight distance and because of the short leverage sufficient power will be provided to move the levers readily and easily and to hold the same in any adjusted position required or desired by the householder.

In the preferred embodiment of my invention the transmission rod 21 is provided with an inwardly bent portion 21^a at its upper end and a similar inwardly bent portion 21^b at its lower end so as to position the rod during operation in close proximity to the window frame.

In Figs. 5 to 7 I have shown a modified form of my invention in which an inclined frame 28 is provided with a series of longitudinally-disposed openings 29 having longitudinally-disposed louvers 27 mounted thereover and adapted upon movement to open and close the openings and by adjustment of such louvers 27 to admit more or less light and air through such openings. As illustrated, each of the louvers 27 is provided on the middle portion of its under surface at positions adjacent to each end with pivot-bearing brackets 30 having pivotally connected thereto the ends of a pair of spaced adjusting levers 31 which are pivoted intermediate their ends on fixed pivot shafts 32 which are mounted in bearings 32^a and extend transversely across the series of louvers. These levers 31 are so pivoted as to provide relatively long weight arms 31^a and relatively short power arms 31^b. The ends of the power arms 31^b are each pivotally connected to a series of longitudinally-disposed lever-connecting members 33 each of which, upon downward and upward swinging movements, is adapted to swing the levers 31 about the pivot shafts 32 and thus to raise and lower and to adjust the louvers in relation to the frame openings 29. Such movement of each of the connecting members 33 is accomplished by connecting its upper end pivotally to the outer end 34^c of a relatively long arcuately-movable transmission link lever 34, which at its opposite inner end 34^a is fixedly mounted on a shaft 35 mounted at its opposite ends in brackets 35^a attached to the window frame, and fixedly mounted on the same shaft 35 is a shorter link lever 34^b thus providing a long weight and short power lever combination. Said short power lever 34^b has connected thereto the upper end of an upright transmission rod 36 which extends downwardly to the lower portion of the window frame and is connected at its lower end with mechanical power-applying means adapted to change the direction of movement and to enable operation of the transmission rod by a simple reciprocating movement. As shown, the lower end of said transmission rod 36 is connected to the upper arm 37 of a bell-crank lever 38 pivoted at 39 on an outside bracket 40 and having its lower arm 41 connected in all respects similar to the device shown in Fig. 4 by a slot and pin connection with a horizontally-disposed straight rod 42 extending through the window frame into the room, and provided within the room with a stationary mounting element 43 and a handle 43^a adapted for

5 manual engagement to reciprocate the rod 42 through the window frame and through the stationary element 43, and thus to move the bell-crank lever 38 and the upright rod 36 which in turn moves the link lever 34^b to rotate the shaft 35 which swings the link-lever 34 and which in turn moves the connecting element 33.

In the construction of Figs. 5 to 7, the adjustable louvers are movable from full open to completely closed position or vice versa by the movement of the short lever 34^b which moves the shaft 35 on which the series of long levers 34 are also fixedly mounted and which have slot and pin connections with the connecting members 33. By this construction, the short lever 34^b and rod 36 have minimum movements and are operable to move the louvers to open and closed position by a short reciprocating movement of the handle 43^a and to hold the same in any intermediate position. The handle for operating such louver-adjusting mechanism is thus adapted to extend within the room only a short distance, and 15 because of such short leverage, sufficient power will be provided to move the levers readily and easily and to hold the same in any adjusted position required or desired by the householder.

20 In this construction also the transmission rod 36 is provided with inwardly bent portions 36^a at its upper end and a similarly inwardly bent portion 36^b at its lower end so as to position the rod in close proximity to the window frame.

Having described my invention, I claim:

30. 1. In a metallic awning for window-frames and the like of the type having a louver-supporting frame fixedly mounted to extend at an acute angle to the vertical members of a window-frame and provided with a series of adjustable louvers pivotally mounted therein to provide a relatively long weight arm and a relatively short power arm, a louver-adjusting mechanism including a reciprocating connecting member pivotally connected with the ends of the power arms of said series of louvers and extending substantially parallel to said louver-supporting frame, 35 an arcuately-movable link-lever mounted at its inner end on a fixed axis on a vertical member of the window-frame within said acute angle and adjacent to the mounting of said louver-supporting frame, said link-lever having a sliding connection at its outer end with said reciprocating louver-connecting member, an upright reciprocable transmission rod of rigid material extending parallel with the window frame and having at its upper end a connection with said arcuately-movable link lever intermediate the ends thereof, and manually-movable operating means, 40 including a pivoted lever connected with the lower end of said upright transmission rod and operable to reciprocate said transmission rod and thereby to rock said transmission link lever to move said connecting members and adjusting levers.
45. 2. In a metallic awning for window-frames and the like of the type having a louver-supporting frame fixedly mounted to extend at an acute angle to the vertical members of a window-frame and provided with a series of adjustable louvers pivotally mounted therein to provide a relatively long weight arm and a relatively short power arm, a louver-adjusting mechanism including a reciprocating connecting member pivotally connected with the ends of the power arms of said series of louvers and extending substantially parallel to said louver-supporting frame, an 50 arcuately-movable link-lever mounted at its inner end on a fixed axis on a vertical member of the window-frame within said acute angle and adjacent to the mounting of said louver-supporting frame, said link-lever having a sliding connection at its outer end with said reciprocating louver-connecting member, an upright reciprocable transmission rod of rigid material extending parallel with the window frame and having at its upper end a connection with said arcuately-movable link-lever intermediate the ends thereof, and manually-movable operating means, 55 including a bell-crank lever pivotally mounted inter-
60. 3. In a metallic awning for window-frames and the like of the type having a louver-supporting frame fixedly mounted to extend at an acute angle to the vertical members of a window-frame and provided with a series of adjustable louvers pivotally mounted therein to provide a relatively long weight arm and a relatively short power arm, a louver-adjusting mechanism including a reciprocating connecting member pivotally connected with the ends of the power arms of said series of louvers and extending substantially parallel to said louver-supporting frame, an 65 arcuately-movable link-lever mounted at its inner end on a fixed axis on a vertical member of the window-frame within said acute angle and adjacent to the mounting of said louver-supporting frame, said link-lever having a sliding connection at its outer end with said reciprocating louver-connecting member, an upright reciprocable transmission rod of rigid material extending parallel with the window frame and having at its upper end a connection with said arcuately-movable link-lever intermediate the ends thereof, and manually-movable operating means, 70 comprising a bell-crank lever pivotally mounted inter-
75. 4. In a metallic awning for window-frames and the like of the type having a louver-supporting frame fixedly mounted to extend at an acute angle to the vertical members of a window-frame and provided with a series of adjustable louvers pivotally mounted therein to provide a relatively long weight arm and a relatively short power arm, a louver-adjusting mechanism including a reciprocating connecting member pivotally connected with the ends of the power arms of said series of louvers and extending substantially parallel to said louver-supporting frame, an 80 arcuately-movable link-lever mounted at its inner end on a fixed axis on a vertical member of the window-frame within said acute angle and adjacent to the mounting of said louver-supporting frame, said link-lever having a sliding connection at its outer end with said reciprocating louver-connecting member, an upright reciprocable transmission rod of rigid material extending parallel with the window frame and having at its upper end a connection with said arcuately-movable link-lever intermediate the ends thereof, and manually-movable operating means, 85 comprising a bell-crank lever pivotally mounted inter-

mediate its ends on the window-frame and having one end connected with said upright transmission rod and the opposite end connected by a slidable pin and slot connection with a horizontally-disposed manually-reciprocable rod passing through the window frame, a stationary mounting element positioned within the room for receiving the end of said rod and having means for adjustably setting the position thereof and a manually-movable handle cooperating with said stationary mounting means and having a connection with said horizontally-disposed manually-reciprocable rod.
